GOLF CLUB

James A. Karns, Akron, Ohio, assignor to Fawick
 Flexi-Grip Company, Akron, Ohio, a corpora-
 tion of Ohio

Application August 6, 1948, Serial No. 147,979

Term of patent 14 years

(Cl. D34—5)

To all whom it may concern:

Be it known that I, James A. Karns, a citizen of the United States, residing at 974 Greenwood Avenue, Akron, Ohio, have invented a new, original, and ornamental Design for a Golf Club, of which the following is a specification, reference being had to the accompanying drawing, forming a part hereof:

Fig. 1 is a side elevational view of a golf club, showing my new design;

Fig. 2 is a fragmentary cross-sectional view of a portion of the handle-grip end thereof, taken on line 2—2 in Fig. 1;

Fig. 3 is a cross-sectional view of the handle-grip of the golf club shown in Fig. 1, taken on lines 3—3 in Fig. 2; and

Fig. 4 is a fragmentary perspective view of the handle-grip end thereof.

The dominant features of my new design are shown in solid lines in the drawing.

I claim:

The ornamental design for a golf club, as shown and described.

JAMES A. KARNS.
